UNITED STATES PATENT OFFICE.

WILLIAM K. CLARK, OF PHILADELPHIA, PENNSYLVANIA, ASSIGNOR OF ONE-HALF TO JOSEPH S. DU QUESNE, OF PHILADELPHIA, PENNSYLVANIA.

PILE-SUPPORTER.

SPECIFICATION forming part of Letters Patent No. 717,659, dated January 6, 1903.

Application filed September 15, 1902. Serial No. 123,505. (No model.)

To all whom it may concern:

Be it known that I, WILLIAM K. CLARK, a citizen of the United States, residing at Philadelphia, in the county of Philadelphia and 5 State of Pennsylvania, have invented certain new and useful Improvements in Pile-Supporters; and I do declare the following to be a full, clear, and exact description of the invention, such as will enable others skilled in 10 the art to which it appertains to make and use the same.

This invention relates to a truss designed for the use of those afflicted with piles; and its object is to provide a truss of this character 15 which obviates certain objections to prior devices of its kind and supports the piles in the most effective manner to obtain positive relief or effect a cure.

The invention consists of a truss embodying certain improved features and combinations of parts, as hereinafter described.

Figure 1 is a perspective view of the truss. Fig. 2 is a side elevation and partial longitudinal section of the pad or support. Fig. 3 25 is a cross-section of the same. Fig. 4 is a bottom plan view of the pad, and Fig. 5 shows a modification of the pad.

1 in the drawings represents a belt or band of such shape and size as to fit about the body 30 of the wearer at a point below the waist, preferably coming immediately over the hips at the sides, over the crotch at the rear, and against the point of greatest extension of the abdomen at the front, thus adapting it to be worn 35 where it is subjected to least motion, leaving the waist portion of the body unencumbered and free to move without restriction. By this means the body movements are not interfered with, while at the same time the parts of the 40 truss are prevented from moving unduly and chafing the wearer. One end of the belt is provided with buttonholes 2 to receive buttons 3 on the opposite end of the belt, whereby the latter may be fastened on the wearer.

45 4 designates a bifurcated front supporting-strap, and 5 a rear supporting-strap, which are connected to the pad 6 and which are provided at their free ends with buttonholes 7 to adjustably engage buttons 8 on the belt.

50 These straps are preferably made of leather or other inelastic material and extend through

the crotch to hold the pad 6 in place. The straps may be secured to the pad in any desired way—by sewing or otherwise fastening them to the pad or by providing the straps 55 with loops 9 to detachably engage hooks 10 on the pad.

The pad 6 is oblong in form and longitudinally curved, its upper supporting-face being concaved to receive the protruding piles and 60 labii and its lower face preferably being convex and tapering toward each end, so as to offer the least possible degree of interference or projection. The length of the pad is such that it is adapted to project slightly beyond 65 the anal opening at front and rear, thus bringing the deepest part of the concavity in alignment with said opening, so that the protruding parts may seat therein and be supported without liability of undue pressure being thrown 70 thereon or of the pad being pressed up into the canal. The purpose of my construction is to avoid the injurious consequences induced by the practice of using a pad which is made to project into the canal or is liable to under 75 pressure, as when the patient sits down, whereby the sphincter is held in an unnatural dilated condition, resulting in an impairment of its functional action when the support is long used. In so doing my device exercises a 80 better curative action, as it does not strain or irritate the parts.

The pad may consist, as shown in Figs. 1 to 3, inclusive, of a hollow elastic base 11, preferably inflated with air and supporting a 85 hard-rubber or wooden saddle 12, longitudinally curved and concaved to act as a receptacle for the protruding parts and a seat for the rectum. This saddle gives the necessary protection to the parts under treatment, while 90 the elastic body 11 forms a cushion which prevents the saddle from exerting excess pressure when the wearer is seated and takes up all shocks or jars. Thus the elastic body gives a desirable cushioning action, while the 95 non-elastic saddle gives the necessary support and prevents the protruding parts from forcing the elastic body down. In some cases, however, I may make the pad of wood or other material and dispense with the cushion, as 100 shown in Fig. 5, in which the pad 6' corresponds to the form of pad shown in the other

figures, but has no elastic or cushioned base. Preferably the saddle is made about one-eighth of an inch thick, three inches long, five-eighths of an inch wide at the center, and 5 diminishing to about one-half an inch width at each end, the concavity at the center being about one-fourth deep, more or less, to suit the patient. These proportions may, however, be varied as occasion may require and 10 as experience may demonstrate as most advisable in fitting the supporter to the patient to secure the best results.

From the foregoing description, taken in connection with the accompanying drawings, 15 the construction and mode of operation of the invention will be readily understood, and it will be seen that the form of pad provided not only protects and supports the protruding parts, but removes the strain, giving rest 20 and comfort to the wearer and causing a rapid amelioration or cure of the disease. This action is of course promoted by the construction of the belt, which prevents the pad from

shifting under body movements, and thus relieves the parts of irritation. 25

Various changes in the form, proportion, and the minor details of construction may be resorted to without departing from the principle or sacrificing any of the advantages of this invention. 30

Having thus described my invention, what I claim as new, and desire to secure by Letters Patent, is—

A pile-support comprising an elongated pad formed of a cushioned base carrying a saddle 35 having a concaved upper face, and means for supporting said saddle on the body, substantially as set forth.

In testimony whereof I have hereunto set my hand in presence of two subscribing witnesses. 40

WILLIAM K. CLARK.
